CLAIM

We claim the ornamental design for power tool, as shown and described.

DESCRIPTION

FIG. 1 is a first perspective view of a power tool according to a first embodiment.

FIG. 2 is a second perspective view of the power tool of FIG. 1.

FIG. 3 is a third perspective view of the power tool of FIG. 1; and,

FIG. 4 is a front view of the power tool of FIG. 1. The broken lines are included for the purpose of illustrating portions of the power tool and form no part of the claimed design.

1 Claim, 4 Drawing Sheets
